UNITED STATES PATENT OFFICE

2,678,612

SIDE WALL CONSTRUCTION FOR RAILWAY FREIGHT CARS

Clarence R. Jones, Youngstown, Ohio, assignor to The Youngstown Steel Door Company, Cleveland, Ohio, a corporation of Ohio

Application March 22, 1950, Serial No. 151,209

2 Claims. (Cl. 105—409)

1

This invention relates to side wall constructions for railway freight cars.

It is an object of this invention to provide side wall constructions for railway freight cars which shall permit the use of standard brackets for securing them to the car underframes and also make possible cars of maximum inside width which shall meet the requirements of the American Association of Railroads in regard to overall width of cars.

A further object is to provide side wall constructions for railway freight cars which shall permit the securing of maximum inside width of cars and embody posts of less than normal depth adapted to be secured to the car underframes by standard brackets.

A further object is to provide side wall constructions of the character indicated particularly adapted for the conversion of wood sheathed box cars and steel sheathed box cars of relatively narrow inside width into modern steel cars of maximum inside width which shall not encroach upon the tunnel clearance prescribed by the American Association of Railroads.

A further object is to provide side wall constructions of the character indicated which shall permit the use of lining boards of substantially standard thickness without altering the boards.

A further object is to provide side wall constructions for railway freight cars which shall embody posts of less than normal depth adapted to be secured to the car underframes by brackets having post engaging flanges of minimum width to which the engaged portions of the post could not normally be secured.

Other objects of the invention will become clear as the description thereof proceeds.

In the drawings forming part of this specification:

Fig. 1 is an elevation of a portion of a side wall construction for railway freight cars embodying the instant invention, parts being broken away.

Fig. 2 is a horizontal section taken on line 2—2 of Fig. 1.

Fig. 3 is a vertical section taken on line 3—3 of Fig. 1.

Fig. 4 is a vertical section taken on line 4—4 of Fig. 3.

Referring to the drawings wherein a preferred embodiment of the invention is illustrated the reference numeral 10 illustrates a side plate of the car side construction. The side plate 10 is of well known construction and embodies a generally Z-shaped section, which extends substantially from end to end of the side wall, having an upper flange 11 of the same slope as the car roof (not shown) secured to the side plate, a vertical flange 12, a substantially horizontal web 13 and a depending vertical flange 14. The side wall construction also embodies door posts, one

of which is shown at 15, a plurality of intermediate posts such as shown at 16 and end posts one of which is illustrated at 17, these posts, as is clearly illustrated in Fig. 1 of the drawings, having their upper ends secured as by means of riveting to the depending flange 14 of the side plate. Fig. 1 illustrates a portion of the side wall construction of the instant invention which extends substantially from a door post to the adjacent end of the construction. It will be understood by those skilled in the art that the side wall construction embodies the door opening 18 and structure extending therefrom to the opposite end of the side wall which is similar in construction and complementary to the construction illustrated. It will also be apparent to those skilled in the art that the side wall construction for the opposite side of the freight car shown will be substantially the same as that illustrated and indicated above.

As is shown more clearly in Figs. 2 and 3 of the drawings the posts of the side wall construction are offset outwardly from the side sill 19 of the car underframe, this side sill being the existing side sill of the underframe where the side wall construction is utilized in the conversion of wood sheathed box cars and steel sheathed box cars of relatively narrow width. The lower end of the door post 15 is secured to the side sill 19 by means of angle members 20 and 21 secured to the opposite faces of the inwardly extending flange 22 of the door post. The securing of the angle members 20 and 21 to the side sill 19 as by means of rivets 23 and 24 is shown in Fig. 2 of the drawings. The intermediate post 16 is secured to the side sill 19 by means of a standard structural bracket 25 clearly illustrated in Figs. 3 and 4 of the drawings and forming the subject matter of the patent to Ditchfield, No. 2,201,826, granted May 21, 1940, to which reference is hereby made.

The gap between the posts and the side sill of the car underframe which results from the outward spacing of the posts relative to the side sill is closed by a substantially Z-shaped member 26 which extends from each door post to substantially the adjacent end of the car. The member 26 has an upstanding flange 27 which is disposed within offset portions 28 in the lower ends of the intermediate posts, an inwardly extending web 29 and a depending flange 30 which abuts the side sill 19. Securement between the intermediate posts and the bracket 25 is obtained by means of flanges 31 and 32 of the bracket which extend upwardly through the web 29 of the member 26 and lie on opposite sides of the inwardly extending flange of each of the posts and are secured thereto as by means of rivets 34 and 35. The flanges 31 and 32 are of minimum width. Metallic sheathing 36 is se-

cured to the depending flange 14 of the side plate and to the outer faces of the intermediate and door posts and the upstanding flange 27 of the bottom member.

In side wall construction for railway freight cars the depth of the intermediate posts commonly used is 3 inches. Where posts of this width are employed the clear inside width of the car is approximately 9 feet 2 inches. By utilizing the instant invention, however, a clear and effective inside width of freight cars of the box car type of 9 feet 6 inches may be obtained and the standard brackets disclosed in the Ditchfield patent utilized without modification thereof. To this end the instant invention utilizes intermediate posts such as post 16 which is less in depth than the depth of the standard intermediate posts. In the preferred embodiment of applicant's invention the depth of the intermediate post 16 is substantially 2½ inches and its construction is such that it permits the use of standard structural brackets, makes possible the securement of an effective inside width of 9 feet 6 inches and permits the utilization of inside lining boards of substantially standard 1½ inch thickness.

As shown in Figs. 2 to 4, inclusive, of the drawings, the intermediate post 16 is substantially Z-shaped in section for a major portion of its length. The post embodies an outer flange 37 to which the metallic sheathing 36 is secured as by means of rivets 38, an inwardly extending flange 39 and an inner flange 40 parallel to the outer flange 37. The outer flange 37 continues to the lower edge of the post which terminates above the web 29 of the member 26. The inner flange 40, however, terminates above the lower edge of the post as indicated at 41. A portion of this flange as shown at 42 is removed and the remaining portion 43 thereof is bent inwardly as indicated at 44 in order to provide an extension of the inwardly extending flange 39 at the lower end of the post. By this construction the depth of the lower end of the post is increased so as to provide additional strength therefor and permit the attachment of the bracket flanges 31 and 32 to the lower end of the post by means of the rivets 34 and 35. The extension 44, as is clearly shown in Fig. 3 of the drawings, lies outwardly of the inner face of the lining 45 which is of substantially standard thickness and terminates above the extension 44.

In addition to its securement to the side sill 19 by means of the angle members 20 and 21 the door post 15 is secured to the member 26 by means of the bracket 46 and gusset 47 as clearly shown in Fig. 1 of the drawings.

It will be apparent that numerous changes and modifications in the details of the invention will be clear to those skilled in the art. It is intended, therefore, that all such modifications and changes be comprehended within this invention which is to be limited only by the scope of the claims appended hereto.

I claim:

1. Side wall construction for a railway freight car comprising a side plate, intermediate and door posts secured at their upper ends to said side plate, said intermediate posts having a portion of major length substantially Z-shaped in cross section and a lower end portion substantially L-shaped in cross section, the web of said Z-shaped portion being of less depth than the depth of standard intermediate posts and embodying inner and outer flanges parallel to said

side wall construction, said lower end portions having an outer inwardly offset flange parallel to said side wall construction and an inwardly extending flange at right angles thereto, a lining of substantially standard thickness secured against said inner flanges of said intermediate posts and terminating at its bottom above said lower end portions, an angular member having an upstanding flange disposed in said offsets and secured to said intermediate posts, said member extending inwardly below said intermediate posts for securement to the underframe of said car, metallic sheathing secured to said side plate and outer faces of said posts and upstanding flange, and standard brackets adapted to secure said intermediate posts to said car underframe, said brackets embodying flanges extending upwardly through said angular member and secured to said inwardly extending flanges, said latter flanges extending inwardly beyond said inner flanges of said posts and terminating outwardly of the inner face of said lining, the inner edge of said bracket flanges also terminating outwardly of the inner face of said lining, said bracket flanges being wider than the distance between said flanges of said Z-shaped portion of said intermediate posts.

2. Side wall construction for a railway freight car comprising a side plate, intermediate and door posts secured at their upper ends to said side plate, said intermediate posts being formed and having a portion substantially Z-shaped in cross section and of less depth than the depth of standard intermediate posts, said portion embodying inner and outer flanges parallel to said side wall construction and a web at right angles thereto, a section of the lower portion of said inner flanges being removed and the remainder thereof being bent inwardly to form an extension of said web of said Z-shaped portion and provide a lower end which is L-shaped in cross section and embodies said extended web and said outer flange of said Z-shaped portion, said latter flange being offset inwardly, a lining of substantially standard thickness secured against said inner flanges of said intermediate posts and terminating above said lower ends, an angular member having an upstanding flange disposed in said offsets and secured to said intermediate posts, said member extending inwardly below said intermediate posts for securement to the underframe of said car, metallic sheathing secured to said side plate and outer faces of said posts and upstanding flange, and standard brackets adapted to secure said intermediate posts to said car underframe, said brackets embodying flanges extending upwardly through said angular member and secured to said extended webs, the inner edge of said extended webs terminating outwardly of the inner face of said lining, the inner edge of said bracket flanges also terminating outwardly of the inner face of said lining, said bracket flanges being wider than the distance between said flanges of said Z-shaped portion of said intermediate posts.
